[57] CLAIM

The ornamental design for a wall mounted lamp assembly, as shown and described.

DESCRIPTION

FIG. 1 is a front perspective view of a wall mounted lamp assembly showing my new design;

FIG. 2 is a top plan view thereof on an enlarged scale;

FIG. 3 is a front elevational view thereof on an enlarged scale;

FIG. 4 is a side elevational view thereof on an enlarged scale, the opposite side being a mirror image;

FIG. 5 is a rear elevational view thereof on an enlarged scale;

FIG. 6 is a bottom plan view thereof on an enlarged scale;

FIG. 7 is a front perspective view of a second embodiment of my new design;

FIG. 8 is a top plan view thereof on an enlarged scale;

FIG. 9 is a front elevational view thereof on an enlarged scale;

FIG. 10 is a side elevational view thereof on an enlarged scale, the opposite side being a mirror image;

FIG. 11 is a rear elevational view thereof on an enlarged scale;

FIG. 12 is a bottom plan view thereof on an enlarged scale.
